BAG HOLDER FOR A VACUUM BAG SEALING MACHINE

Ralph S. Randall, San Francisco, Calif., assignor to Vak-U-Pak Corporation, San Francisco, Calif., a corporation of California

Application December 5, 1955, Serial No. 550,921

3 Claims. (Cl. 53—371)

The present invention relates to improvements in a bag holder for a vacuum bag sealing machine of the type described in my co-pending application, Serial Number 486,797, and its principal object is to provide a bag holder that will readily engage in the open end of a bag along opposite edges thereof, and will hold the two confronting sheets of the bag in slightly spaced relation, so as to form a slit between the same through which air may be exhausted from the bag, and an inert gas substituted, if desired.

The vacuum bag sealing machine described in my co-pending application comprises in its principal features, a platform adapted to receive a number of open-ended bags thereon in side-by-side relation, a cover hinged to the platform and operable for lowering upon the same to form a housing therewith, means for evacuating the housing, heat-sealing elements adapted for lowering upon the open ends of the bags for sealing the same, and means for operating the heat-sealing elements in timed relation to the evacuating process.

When the bags are originally placed upon the platform, it becomes necessary to properly position the same with respect to the descending heat elements, and it is desirable that the ends of the filled bags be flattened out prior to the application of the heat-sealing elements.

In the machine described in the co-pending application, I provided for this purpose a pair of co-operating spring fingers which would advance slightly ahead of the sealing elements, and which would spread upon the end of the bag for flattening the same.

This arrangement, while operating satisfactorily, gave no particular guide to the operator in fixing the bags, and in the present invention it is proposed to provide a bag-anchoring means which allows the operator to definitely position the bags in their proper place, without variation in relative position, and to anchor each bag in a swift movement.

It is further proposed to provide an anchoring means of the character described which acts on the extreme end of the bag, leaving an immediately adjacent portion of the neck of the bag free for the sealing operation.

Another object of the present invention is to arrange the holding means in such a manner as to leave a slit between the two sheets of the bag, the slit extending through the full width of the bag, to facilitate the passage of a gas therethrough.

Further objects and advantages of my invention will be disclosed as the specification continues, and the new and useful features of my bag holder will be fully defined in the claims attached hereto.

The preferred form of my invention is illustrated in the accompanying drawing, forming part of this application, in which:

Figure 1 shows a plan view of my bag holder, as applied to the platform of a bag sealing machine;

Figure 2, a front view of the bag holder;

Figure 3, a rear view of the same;

2

Figure 4, a section taken along line 4—4 of Figure 2; Figure 5, a section taken along line 5—5 of Figure 2; Figure 6, an end view of the holder as seen from arrow 6 of Figure 2; and

5 Figure 7, an end view as seen from arrow 7 of Figure 2. While I have shown only the preferred form of my bag holder, it should be understood that various changes or modifications may be made within the scope of the claims attached hereto, without departing from the spirit 10 of the invention.

Referring to the drawing in detail, the platform 1 of the vacuum bag sealing machine is shown fragmentarily, it being sufficient for the purpose of the present invention to indicate that it is mounted horizontally and is substantially rectangular and adapted to accommodate a number of previously filled bags thereon in side-by-side relation.

A special anchoring means is provided for each bag, and each anchoring or holding means comprises in its general features, a strip 2, preferably made of metal and 20 adapted for securing upon the platform by means of screws 3, in parallel relation to the front edge of the platform, a block 4 rising from one end of the strip, a stop 5 mounted upon the other end of the strip, a rod 6 having its ends mounted in the block and in the stop, 25 respectively, and a second block 7 slidable on the rod, and a spring 8 coiled about the rod 6 and tensioned to urge the second block away from the first block and toward the stop, the two blocks having fingers 9 and 10 projecting rearwardly over the platform, and engageable 30 in opposite edges of the open end of the bag for stretching the latter. The bag is shown at 11.

The strip 2 is straight, rectangular in form and relatively thin as compared with its width. It is of a length in excess of the width of the widest bag to be handled in 35 the machine.

The block 4 and the stop 5 have aligned holes and their principal function is to support the rod.

The finger 9 projects rearwardly from the block 4 and has a substantially flat bottom face 12 spaced from the 40 platform by a suitable distance to allow of the accommodation of a layer of cork 13 underneath the same, with a certain amount of clearance between the bottom of the finger and the layer of cork, so as to allow one side of the bag to be readily slipped over the finger.

45 The finger is in the form of a transversely tapered blade presenting a relatively thin outer edge, as at 14, and a heavier inner edge, shown at 15. The sharp outer edge is intended for engagement in the bag fold, while the inner edge serves the function of a spacing medium for the two opposing sheets of the bag. The outer edge is also formed with a slight outward taper 16 to more firmly grip the fold of the bag.

The block 7 is slidable on the rod 6, and has a flat 55 bottom face 17 lightly bearing on the strip 2 so as to hold the block against rotation. Its finger 10 is similar to the finger 9 previously described, its outer edge being relatively sharp, as at 14', and its inner edge relatively heavy, as shown at 15'.

The spring 8 normally crowds the block 7 upon the 60 stop 5. The thin outer edge 14' is also tapered outward, as at 16, to secure a firmer grip in the fold of the bag.

In operation:

The bag 11, which has been previously filled with sliced 65 meats, sausages, or other perishable foods, is placed on the platform rearwardly of the anchoring means by an operator standing in front of the machine. In this position the open end of the bag faces the anchoring means, and the movable block 7 bears against the stop 5.

70 The operator then engages the left side fold of the bag, as shown in Figure 1, over the left finger, pulls the bag toward the right until its right fold projects beyond the

right finger, and then slips the right fold over the right finger.

Upon release of the bag, the spring 8 pushes the left finger to the left as far as it will go, and the two fingers now cooperate in stretching the bag, with the two sheets arranged in spaced relation and with a straight slit formed between the sheets, the width of the slit being commensurate with the thicknesses of the inner edges of the fingers.

While the bag is in this position, it may be readily evacuated and re-filled with an inert gas, if desired.

The sealing element, shown in dotted lines at 22, has been fully described in the co-pending application, and is made to descend upon the bag and the under-lying layer of resilient material immediately rearwardly of the fingers, in timed relation to the evacuating operation.

The strip 2, if desired, may be made in two sections independently and adjustably secured upon the platform in aligned relation, so as to allow the overall length of the strip to be adjusted for different sizes of bags.

The layer 13 may be made of cork, as described in the co-pending application, or of rubber or any resilient, heat-resisting and elastic material suited for this purpose. It may be positioned with its front edge disposed underneath the fingers, as shown in the drawing, or it may be positioned with its front edge disposed rearwardly of the fingers, so as to leave the space underneath the fingers unoccupied for easier application of the bag.

Where the endless belt structure described in the co-pending application is substituted for the rigid platform, the strips of the present invention may be secured upon the belt at their centers, so that the ends of the strips may freely swing away from the belt where the latter curves about the sprockets or rollers supporting the same.

The spring 8 will, of course, be suitably tensioned to perform its desired function, a heavier bag requiring a heavier spring than a light bag.

I claim:

1. A holder for the open end of a bag lying on a platform, comprising a straight strip of rigid material secured upon the platform and having a block rising from one end thereof, with a finger projecting from the block over the platform in spaced relation thereto, a stop mounted on the other end of the strip in opposing re-

lation to the block, a rod mounted in the block and the stop, a second block slideable on the rod and having a second finger mounted thereon in registering relation to the first finger, and a spring mounted on the rod and operable for urging the second block away from the first block, the fingers being engageable in the open end of the bag for stretching the same.

2. A holder for the open end of a bag lying on a platform, comprising a straight strip of rigid material secured upon the platform and having a block rising from one end thereof, with a finger projecting from the block over the platform in spaced relation thereto, a stop mounted on the other end of the strip in opposing relation to the block, a rod mounted in the block and the stop, a second block slideable on the rod and having a second finger mounted thereon in registering relation to the first finger, and a spring mounted on the rod and operable for urging the second block away from the first block, the fingers being engageable in the open end of the bag for stretching the same, and having outer edges tapering outwardly for anchoring engagement in the bag end.

3. A holder for the open end of a bag lying on a platform, comprising a straight strip of rigid material secured upon the platform and having a block rising from one end thereof, with a finger projecting from the block over the platform in spaced relation thereto, a stop mounted on the other end of the strip in opposing relation to the block, a rod mounted in the block and the stop, a second block slideable on the rod and having a second finger mounted thereon in registering relation to the first finger, and a spring mounted on the rod and operable for urging the second block away from the first block, the fingers being engageable in the open end of the bag for stretching the same, and the fingers being in the form of tapered blades having relatively thin outer edges engaging the bag material and heavier inner edges for spacing the bag sheets to form a lengthwise slit in the open end of the bag.
